UNITED STATES PATENT OFFICE.

JACOB HOOK, OF RENO, NEVADA.

SHIELD FOR COVERS FOR RADIATORS.

1,329,836.

Specification of Letters Patent. Patented Feb. 3, 1920.

Application filed May 23, 1918. Serial No. 236,198.

To all whom it may concern:

Be it known that I, JACOB HOOK, a citizen of the United States, residing at Reno, in the county of Washoe and State of Nevada, 5 have invented certain new and useful Improvements in Shields for Covers for Radiators, of which the following is a specification, reference being had therein to the accompanying drawings.

10 This invention relates to a shield for a cover for radiators, and has for its object the provision of a simple and efficient shield to protect a cover for radiators and at the same time to prevent a person from coming 15 in direct contact with the cover of a radiator, which cover would, undoubtedly, be heated to a higher degree of temperature than the shield when the radiator upon which the shield and cover is placed, is 20 heated.

With this and other objects in view, the invention consists of certain novel constructions, combinations, and arrangements of parts, as will be hereinafter fully described 25 and claimed.

In the drawings:

Figure 1 is a view in side elevation of the preferred embodiment of my shield.

Fig. 2 is a vertical sectional view taken 30 on line 2—2, Fig. 1, and looking in the direction of the arrows.

Fig. 3 is a horizontal, sectional view taken on line 3—3, Fig. 1, and looking in the direction of the arrows.

35 Fig. 4 is a fragmentary, sectional view taken on line 4—4, Fig. 1.

Fig. 5 is a perspective view of another embodiment of the present invention.

Referring to the drawings by numerals, 1 40 designates the body of my shield, which is provided with an enlarged central opening, and upon the edges 2 of this opening is mounted a frame 3, which frame 3 is substantially S-shaped in cross-section (Fig. 4),

45 constituting a substantially double U-shaped structure; in the outer U-portion 4 is mounted a wire mesh 5, and in the inner U-portion 6 is positioned the edge 2 of the body or main portion 1 of the shield.

50 The lower marginal edge 7 of the body

1 is rolled, and in this rolled edge 7 is positioned a reinforcing rod or wire 8.

The shield is mounted upon cover 1^a, and said cover is mounted on the radiator 9. For the details of construction of said 55 cover 1^a see my U. S. Patent, #1,275,928, issued August 13, 1918.

In the embodiment shown in Fig. 5, I have extended one side of the body 1 downward, as at 1^a, this extension 1^a, being adapted to 60 be placed on the side of the radiator (see dotted lines 9, Fig. 2) next to the wall of a building to prevent the heat from the radiator injuring the wall if the radiator should be placed close thereto, as is often the case. 65 In other respects, the structure of the embodiment shown in Fig. 5 is similar to the embodiment shown in Figs. 1 to 4, except that in the embodiment depicted in Fig. 5, the edges 10 of the shield are not rolled as in 70 the embodiment shown in Figs. 1 to 4.

From the foregoing description, it will be seen that a very simple and efficient means has been produced for the purpose of connecting or securing the wire mesh screen to 75 the body of the shield.

I wish it to be understood that I reserve the right to make such alterations, modifications, and changes to my invention as will be obvious to one skilled in the art to 80 which this invention relates, and as shall fairly fall within the scope of the appended claim.

What I claim is:

The combination with a radiator, of a removable cover mounted thereon, a shield mounted on said cover, said shield comprising a body extending over the top of said cover and parallel with its sides and having a central opening, and a wire mesh secured 90 to the body and closing said central opening and extending parallel with both sides of said radiator, substantially as shown and described.

In testimony whereof I hereunto affix my 95 signature.

JACOB HOOK.

Witnesses:

PETER DOHR,
MAE COOSIGLIA.
